CLAIM

We claim the ornamental design for a buggy, as shown and described.

DESCRIPTION

FIG. 1 is a front left perspective view of a buggy embodying the design;

FIG. 2 is a front elevation view of the buggy;

FIG. 3 is a rear elevation view of the buggy;

FIG. 4 is a left side elevation view of the buggy;

FIG. 5 is a right side elevation view of the buggy;

FIG. 6 is a top plan view of the buggy; and,

FIG. 7 is an additional front left perspective view of the buggy.

Features shown with broken lines form no part of the design to be patented.

The design is embodied in a buggy for transporting a small child.
